UNITED STATES PATENT OFFICE.

ELBRIDGE F. BIGGS, OF FREDERICK, MARYLAND.

ELECTRICAL PIANO PLAYER.

Application filed January 7, 1921. Serial No. 435,647.

To all whom it may concern:

Be it known that I, ELBRIDGE F. BIGGS, a citizen of the United States, residing at Frederick, in the county of Frederick and 5 State of Maryland, have invented certain new and useful Improvements in an Electrical Piano Player; and I do hereby declare the following to be a full, clear, and exact description of the invention, such as will 10 enable others skilled in the art to which it appertains to make and use the same.

The object of the invention is to provide a player attachment applicable to the key board of any instrument of the piano or 15 organ type and which is adapted to use record rolls of the ordinary or commercial forms; an attachment in which the key operating elements are electrically actuated under the control of the record sheet; means 20 whereby the rate of feeding movement of the record is regulated by the operator to suit the character of the composition which is being reproduced so that the expression may be controlled by the means with which 25 the instrument is equipped; and with these general objects in view, together with subsidiary related objects which will appear in the course of the following description, the invention consists in a construction, 30 combination, and relation of parts of which a preferred embodiment is illustrated in the accompanying drawings, wherein:

Figure 1 is a plan view of the player attachment applied in the operative position 35 to a key-board.

Figure 2 is a transverse sectional view on the plane indicated by the line 2—2 of Figure 1.

Figure 3 is a longitudinal section on the 40 plane indicated by the line 3—3 of Figure 1.

Figures 4 and 5 are transverse sectional views on the planes indicated respectively by the lines 4—4 and 5—5 of Figure 1.

Figure 6 is a plan view enlarged of the 45 tracker or contact roll, and the tracker board, the former being broken away to show the latter.

Figure 7 is an enlarged view in plan to 50 show particularly the means for actuating the feed roll or spool and for effecting the rewinding movement of the spindles which carry the record roll.

Figure 8 is an enlarged detail sectional view to show the relation between the contact terminals of the circuits which actuate 55 the key operating plunger.

Figure 9 is an end view of the case to show the means for adjusting the same with relation to the key-board.

Figure 10 is an edge view of the same. 60 Figure 11 is a detail section on the plane indicated by the line 11—11 of Figure 7.

Figure 12 is a detail section on the plane indicated by the line 12—12 of Figure 7.

Figure 13 is a detail view on the plane 65 indicated by the line 13—13 of Figure 11.

Figure 14 is a detail plan view of the tracker board, the tracker roll and the frame in which the tracker roll is journaled.

Figure 15 is a diagrammatic view of the 70 electric circuits.

Figure 16 is a sectional view, and

Figure 17 is a plan view of the solenoid.

Within a suitable frame or casing 10 which is adapted to be terminally supported 75 upon the key-board or by means of the blocks at the terminals of the key-board of an instrument of the piano type are arranged the vertically movable key operating elements consisting of plungers having stems 80 11 and cushioned buttons or knobs 12 for contact with the keys of the instrument, said plungers being normally and yieldingly held in an elevated or retracted position by means of springs 13 and being connected 85 with cross heads 14 carrying the armatures 15 of solenoids 16, and said solenoids preferably being of the double type indicated, and serving to insure the accurate reciprocatory movement of the key actuating plungers. The windings of each solenoid are 90 connected to bus bars 17 by wires 18, it being understood that the apparatus may be actuated from the ordinary house lighting system or any equivalent thereof. It will 95 also be understood that while magnets are preferably employed as the means for actuating the plungers, the solenoid form of magnet is especially adapted to the purpose by reason of the fact that a direct reciprocatory movement of the plungers can be effected thereby, the armatures of the twin solenoids serving as guiding means for the same.

The tracker board or plate 19, having slots or openings 20 (Figures 6 and 8) is preferably made of black fiber or any other suitable non-conducting material. Parallel with the tracker board is arranged a tracker roll 22 idly mounted for revoluble movement and constituting one terminal of the circuit as a contact 22' on board 19 constantly wipes it and is connected by a wire 22^a to a source of energy which for the purpose of illustration is shown as a battery 22^b (Figure 15). Said roll is terminally mounted on trunnions 23^a of bearings in the frame consisting of pins 23 slidable vertically in the tracker board 19 and connected by a cross bar 24 and yieldingly impelled toward the tracker board by springs 25 disposed around said pins. The frame has at an intermediate point, a bearing roller 26 (Figures 4 and 14) arranged in the path of movement of a shifting lever 27 fulcrumed as at 28 to the frame 10 and adapted when swung laterally in the direction indicated by the arrow in Figure 1 to pass under the roller and thereby lift the frame and with it the tracker roll so as to permit the introduction and removal of the record sheet. In the operation of the mechanism the record sheet is held in close contact with the surface of the tracker board by means of said roll 22 to provide for the successive registration of the openings in said sheet with the slots or openings in the tracker board. The electrical circuit which includes the source of energy and the terminal represented by the tracker roll 22 also includes a switch element 29 which is connected to the source of energy by a wire 29^a and which is carried by but insulated from the shifting lever 27, and a pair of switch elements 29^b which are carried by a bracket 29^c and which are connected by wires 29^d to the bus bars 17. When the lever 27 is moved to displace the tracker roll from the tracker board the circuit is opened.

Arranged beneath the tracker board and respectively in alinement with the openings or slots 20 thereof, are the terminals 30 each of which is connected to a magnet by a wire 33, said terminals having curved or hook shaped extremities 31 adapted for engagement with the tracker roll through the openings in the record sheet as they successively come into registration with the openings or slots in the tracker board, said terminals being yieldingly held in position to effect such contact and thus close the circuits respectively through the magnets, by leaf springs 32. The terminals 30 (Figures 6, 8 and 15) are preferably of steel spring wire or like material, which maintain an effective contact with the surface of the tracker roll during the rotation of the latter due to the movement of the record sheet between the roll and the tracker plate.

The record roll 34, as in the ordinary practice is provided with terminal sockets for engagement with the record roll spindles 35 and 36, the former being spring actuated and the latter being revoluble and having a sprocket and chain connection 37 with a rewinding disk 38 idly mounted for rotation upon the drive spindle 39 upon which is keyed the driving head 40.

The usual take up roll 41 is provided with a spindle 42 mounted in suitable bearings 43 in the frame, (Figure 7) and loosely and revolubly mounted thereon is a sprocket wheel 43^a connected by a chain 44 with a sprocket wheel 45 loosely mounted upon the drive shaft or spindle 39. Sprocket wheel 45 carried by the driving head 40 is yieldingly connected with the shaft by a spring 46, to the end that when the driving head is moved toward the left to cause the engagement of the pin 47 of the sprocket wheel 43^a with the socket 48 in the take up roll 41, the spring 46 transmits motion from the shaft through the disk 45 to the drive head. In turn the sprocket wheel 45, operates chain 44 and the sprocket 43^a to cause the winding movement of the take up roll to feed the record ribbon from the record roll thereto. Obviously the engagement thus secured is such as to permit of yielding due to the resilience of the spring 46 in the event of excessive strain to avoid injury to or fracture of the parts of the driving mechanism due to the resilience of the spring 46. The movement of the drive head and the sprocket wheel 43^a to effect the coupling of the take up roll with the drive spindle is effected by means of a shifting rod 50 having a terminal yoke 51 which is in engagement with the drive head 40 and the hub 52 of the sprocket wheel 43^a. The shifting rod is yieldingly held in a neutral position by a spring 53 and is movable in one direction or the other by the contact of the shifting lever 27 with the spaced pins 54 and 55. When the lever is moved to the right a clutch pin 56 on the drive head is arranged in engagement with a pin 57 on the gear 38 to cause the communication of rewinding movement to the record roll spindle 36.

The spring 46 acts to cushion the transmission of motion from the drive shaft and neutralize or compensate for irregularities in the rate of actuation thereof, and it is provided with terminal extension pins 46^a and 46^b for engagement respectively with the sprocket wheel 45 and a collar 46^c secured to the drive shaft.

Also, preferably carried by the rewinding spindle 36 is a brake disk 58 in operative relation with which is arranged a brake shoe 59 carried by a stem 60 actuated by a spring 61, said stem being connected by a rod 62 with the shifting rod 50, so

that when the latter is moved to the right to effect the clutching of the rewinding spindle with the drive shaft, the brake shoe 59 is removed from the brake disk. When 5 the parts are adjusted for the playing of a record, the clutch mechanism being arranged to communicate motion from the drive spindle 39 to the take up roll 41, the contact of the brake shoe with the disk 58 10 serves to yieldingly retard the rotary movement of the spindle 36 and hence of the record roll, to prevent the too rapid unwinding movement thereof and hence the slackening of the record sheet.

15 The drive shaft receives motion from an operating lever 63 mounted at the front of the mechanism within convenient reach of the operator and connected with the drive shaft by means of a double ratchet gear 64 20 consisting for example of the bevel pinions 65 and the intermediate pinion 66 secured to the drive spindle. Obviously by this arrangement motion in the same direction is imparted to the drive spindle by oscillatory 25 movement in opposite directions of the operating lever.

In order that a proper tracking of the record with reference to the tracker board may be secured, or in order that adjustment 30 may be made in the event that the record does not properly track, the record spindle 36 is made longitudinally movable for actuation by a cam 67 (see Figure 12) of which the stem 68 is provided at the front 35 of the case with a thumb or finger knob 69, said spindle being provided with elongated gear teeth 70 for engagement with the gear 58 to allow for adjustment. The spindle 35 is yieldingly mounted, and is held in 40 proper position in opposition to the spindle 36 by means of a spring 71.

To provide for the proper positioning of the frame of the apparatus upon the frame of the piano or other instrument and in proper relation with the key-board, the end 45 walls 72 thereof are provided in their lower edges with guide grooves 73 in which are fitted adjustable positioning wedges 74 to bear upon the end cleats of the board.

50 As a means of regulating and rendering uniform the rotary movement of the roll 41 it may, as indicated in Figures 7, 11 and 13, be provided with a worm gear 75 meshing with a worm 76 of which the spindle 77 is mounted in a pivotal bearing 78 and is fitted for example with a fly wheel 79. Said spindle is positioned, to cause engagement 55 of the worm with the gear 75, by means of a cam 80 carried by an arm 81 attached to the gear shifting rod 50 engageable with a roller 80a on spindle 77, to the end that the meshing of the worm and gear is effected only when the mechanism is operating in the playing of a record. Gear 60 75 and worm 76 are disengaged when the

rod 50 is moved to shift the gears to rewinding position.

In practice it is preferred to supplement the action of the tracker roll 22 in maintaining the proper position of the record 70 ribbon with reference to the tracker board by auxiliary idle guiding rolls 82 arranged respectively at opposite edges of the tracker board.

It is preferred as indicated in Figures 75 16 and 17 to employ a special form of double solenoid as a means of securing the energy necessary to effectively operate the keys of the instrument, such construction involving the stationary or armature core 80 83 in addition to the movable cores 84, both of which are subject to the influence of the winding 85 and are provided with interfitting coned and cavitated faces 86 and 87, the movable cores being connected (see 85 Figure 16) by a cross head or bridge piece 88 for engagement by the upper end of the retracting spring 13.

Having thus described my invention what I claim is:—

1. A player attachment for pianos consisting of a casing, slideable plungers in said casing engageable with the piano keys, said plungers each having a stem, cross heads within the casing and disposed transversely 95 on said stems, an electro-magnet to actuate each cross head, each magnet having a plurality of stationary armatures, and movable armatures slideable toward and from said stationary armatures and depending from the adjacent cross head one on each side of the stem thereof and constituting guide means for the stem.

2. A player attachment for pianos consisting of a casing, slideable plungers in the 100 casing engageable with the piano keys, cushions on said plungers to directly engage piano keys, said plungers having stems passing through the bottom wall of the casing and carrying said cushions at 105 their lower ends, cross heads within the casing and fastened transversely on the stems, return springs surrounding the stems and engageable with said cross heads and the base wall of the casing, electro-magnets 110 to actuate the cross heads, each magnet having a plurality of stationary armatures, movable armatures slideable toward and from said stationary armatures and depending from the adjacent cross head one 115 on each side of the stem and constituting guide means for the stem, and means to establish electric circuits through said electro-magnet under control of a record.

3. In an electrical player attachment for 120 pianos having electro-magnetic means for actuating the piano keys, a tracker member, a conducting roll in circuit with said electro-magnetic means disposed above the tracker, said tracker member being slotted 125 130

below said roll, circuit closing contacts in circuit with the key actuating means and fastening against the under surface of the tracker, said contacts having portions extending into the slits of the tracker, and arcuate terminals on said portions to directly engage the record.

In testimony whereof I affix my signature in presence of two witnesses.

ELBRIDGE F. BIGGS.
